UNITED STATES PATENT OFFICE

ROY H. GERARD, OF SAN FRANCISCO, CALIFORNIA, ASSIGNOR, BY MESNE ASSIGNMENTS, TO BOWEN MOTORS COMPANY, A CORPORATION

INTERNAL-COMBUSTION ENGINE

Application filed September 28, 1926. Serial No. 138,178.

My invention relates to internal combustion engines and particularly to valve mechanism for the same and one of the objects of the invention is the provision of an internal combustion engine in which each of the main or power cylinders is provided with a single port thru which fuel is introduced into the cylinder and burned gases exhausted therefrom. 5
Another object of the invention is the provision in an engine of the character described of improved valve means for controlling the single port in each cylinder. 10
Another object of the invention is the provision in an engine of the character described of a single valve cylinder opening at one end into the exhaust manifold and at the other end into the intake manifold and provided with a single port opening into 15 the power cylinder, together with a selector valve the movement of which determines which end of the valve cylinder is in communication thru the port with the power cylinder. 20
Other objects of the invention will be set forth in the following description of the preferred embodiment of my invention which is illustrated in the drawings forming part of the specification. It is understood that I do 25 not limit myself to the showing made by the said description and drawings as I may adopt variations of my preferred embodiment within the scope of my invention as set forth in the claims. 30

Referring to the drawings:

Figure 1 is a vertical sectional view taken in a plane passing thru the longitudinal axis of one of the cylinders of an engine embodying my invention, the plane of section is 40 indicated by the line 1-1 of Figure 2.

Figure 2 is a plan view of a four-cylinder engine embodying my invention, the direction of the view being indicated by the arrow 2 of Figure 1.

Figure 3 is an elevation of the upper portion of the engine, the direction of view being indicated by the arrow 3 in Figure 1.

A portion of the housing is shown broken away to disclose the underlying structure.

Figure 4 is an elevation of the upper por-

tion of my engine, the direction of the view being indicated by the arrow 4 of Figure 1. The housing is shown broken away to disclose the cam shaft.

Figures 5, 6, 7 and 8 are largely diagrammatic views showing a cylinder in vertical section with its associated valve mechanism. The plane of section of each of these figures is the same as that of Figure 1.

In terms of broad inclusion, the internal combustion engine of this invention comprises a cylinder block in which one or more power cylinders are incorporated, each associated with a transversely extending valve cylinder, preferably located across the upper end of the cylinder in a vertically arranged engine. The valve cylinder is connected with the power cylinder by a single port approximately in the middle of the valve cylinder; and one end of the valve cylinder is connected into the fuel supply manifold while the other end is connected to the exhaust manifold. The valve cylinder is divided by a movable wall or selector so that with movement of the selector to one side or the other of the main cylinder port, either the intake manifold or the exhaust manifold, as the case may be, is placed in communication with the power cylinder. In order to secure a highly sensitive and close control of the port opening, it is preferable to mount the selector valve within a sleeve rigidly projecting into the valve cylinder; and to arrange a movable sleeve between the fixed sleeve and the cylinder wall. The fixed sleeve has a port which is in line with the main cylinder port, and the movable sleeve has a port adapted to be brought into register with the main cylinder port so that the main cylinder port is also controllable by the movable sleeve. The function of the selector valve is to determine which side of the valve cylinder, that is exhaust or intake, is placed in communication with the cylinder port;

and the function of the sleeve is to close and open this port at the proper times independently of the movement of the selector valve to its position on one side or the other of the port. Means are provided operated immediately from the piston for harmonizing 95 100

the movements of the selector and the sleeve valves; and this means preferably comprises a cam shaft driven by suitable gear connection with the crank shaft of the engine, to 5 which cam shaft the valves are operatively connected by suitable means.

In the following detailed description, reference will be made principally to a single cylinder and its associated mechanism as 10 indicated in Figure 1. The principles of this invention may be applied to any number of cylinders and in Figures 2 and 4 is shown a four-cylinder embodiment.

Mounted in suitable bearings 2 in the bed 15 frame 3 is the crank shaft 4 connected by the connecting rod 6 with the power piston 7 slidably arranged in the usual fashion in the cylinder 8. The bottom of the bed frame comprising the crank case is closed 20 by the cover plate 9 having the heat radiating flanges 11 disposed thereon and carrying on the inner bottom surface a trough 12 into which the dipper 13 on the end of the connecting rod 6 is adapted to splash. It 25 will be understood that there is a trough 12 disposed below each crank and connecting rod. Extending longitudinally of the cover plate 9 on each side thereof is a trough 14 in communication with the ends of the 30 troughs 12, so that oil splashed on the side walls of the enclosing casing runs down into the troughs 14 and thence into the troughs 12. The chamber or space 16 below the troughs acts as a sump for the collection of oil in the usual manner. The cylinder block of which the cylinder 8 forms 35 a part is suitably secured to the bed frame 3 by the cap screws 17 and is provided with suitable passages 18 for the circulation of 40 the cooling water in accordance with the standard or desired practice. Mounted on the top of the cylinder block and separated therefrom by the usual gasket 19 is a valve block 20 in which are cored the cooling water 45 passages 21, the uppermost of which is closed by the cover plate 22. Also formed in the valve block and extending transversely therethru over the end of each cylinder is a valve cylinder 23 opening at one end, on 50 the left side of Figure 1 thru the passage 24 into the exhaust manifold 26, rigidly secured on the side of the valve block. At the opposite end the valve cylinder opens thru the passage 27 into the intake manifold 55 28. The intake manifold is secured rigidly on the right hand side of the valve block as viewed in Figure 1 and receives its fuel mixture thru a passage 29 extending thru the valve block in register with a passage 60 31 in the exhaust manifold. This passage extends downwardly to the carburetor 32, of any well known type, and because of its inclusion within the walls 33 over which the burned gases of combustion sweep, the fuel 65 gases are suitably heated and liquid particles

of fuel are vaporized upon the hot walls. The carburetor is fed from the usual float chamber 34, which in turn receives liquid fuel thru the pulsometer 36 connected by conduit 37 with the fuel tank. The pulsometer is also connected by the electric conductors 38 with a suitable source of electric energy. Formed in the valve block in register with each cylinder bore is the explosion chamber 41 provided with a spark plug 42 75 connected by suitable conductors 43 to the distributor head 44 of any well known type and rotatably mounted for control by the lever 46 in the usual way.

The explosion chamber is preferably conical in form and opens at its upper end in a passage 47 extending entirely around the valve cylinder and out of which opens the port 48 thru which all fuel and burned gases of combustion pass into and out of the power cylinder from and to the valve cylinder.

Extending into the valve cylinder from the left side, as viewed in Figure 1, is a sleeve 49 having the port 50 in register with the port 48 and assembled between the rings 51 and 52. The ring 51 is caught between the shoulder at the end of the valve cylinder and a compressible gasket 53 facing a flange formed on the bushing 54, the interior of which is given the shape of a Venturi tube. The bushing is made heavy and is in thermal contact with the metal of the valve head so as to protect the fixed sleeve which it lines from the effects of the hot gases which pass thru this end of the valve cylinder. The ring 52 is interposed between the end of the fixed sleeve 49 and the end of the fixed sleeve 55, which at the other end seats in the intake manifold 100 around the passage 27. Slidably disposed in the valve cylinder, between its walls and the fixed sleeve 49 is the sleeve valve or movable sleeve 56 having the piston rings 57 and having a port 58 adapted to be brought 105 into register with the port 48. Preferably this port is somewhat wider than the port 48, as shown in the drawings. Slidably mounted within the fixed sleeve 49 is the selector valve 61, slightly dished as shown, and pointing toward the exhaust manifold. On the concave side which faces the intake manifold, the selector is provided with ribs 62. The reason for this construction is to 110 permit the heat which the selector takes up from the exhaust gases to be utilized in vaporizing any liquid particles which may be entrained in the fuel stream. The separate piece construction and mounting of the fixed sleeves is suggested by the difficulty of 115 perfectly alining parts subject to such wide ranges of temperature. By the construction adopted, the fixed sleeves center themselves and the parts work freely without 120 125 130

binding, the compressible gasket 53 permitting expansion.

Means operated mediateley from the power pistons is provided for actuating the selector 61 and the sleeve valve 56. Bolted on the right hand side of the cylinder block, as viewed in Figure 1, is a bracket plate 66 on which brackets 67 are formed. Journaled in these brackets in suitable bearings 68 is a cam shaft 69 connected by the gears 71, shaft 72 and gears 73 with the crank shaft 4. The cam shaft is also utilized thru the gears 74 and shaft 76 to drive the distributor rotor. The cam shaft is provided with a cylindrical cam 77 and a pear-shaped cam 78 opposite each valve cylinder. Engaged with these cams are rocker arms 79 and 81 respectively, pivotally mounted on the shaft 82 mounted in the brackets 83. The rocker arm 79 is pivotally connected by the link 84 with the sleeve valve 56; and the rocker arm 81 is pivotally connected by means of the link 86 with the head 87, adjustably fixed on the rod 88, fixed at the other end in the selector 61 and passing thru the gland 91 in the wall of the intake manifold. Although all of the rocker arms are pivotally mounted on the same shaft 82, the rocker arms are separated and shown as though mounted on separate shafts in the diagrammatic Figures 5, 6, 7 and 8, an examination of which will disclose the method of operation of these parts. The parts are so shaped and assembled with relation to each other that, as shown in Figure 5, with the piston 7 at the top of the intake stroke, the sleeve valve 56 is stationary with its port 58 in register with the cylinder port 48, and the cylinder valve 61 is on the exhaust side of the port 50, so that the aligned ports and right hand side of the valve cylinder complete a free passage between the explosion chamber 41 and the intake manifold 28. The valves remain in this position during the intake stroke, but at the bottom of this stroke and prior to the beginning of the compression stroke, as shown in Figure 6, the cam 77 has moved the sleeve 56 to close the port 48. In order to accommodate the trapped air between the end of the sleeve and the ring 51, a passage 92 is formed within the wall of the valve cylinder. As the piston ascends on the compression stroke, the selector 61 is moved toward the port 50 and at the moment of explosion, as shown in Figure 7, the selector covers the port 50 and the sleeve 56 has started its recovery movement toward the right. As the piston reaches the bottom of its explosion stroke, the selector has reached the intake manifold, or right hand side of the port 50, and as the piston starts upwardly on the exhaust stroke, the sleeve valve has moved backwardly to again align the ports 58 and 48, thus clearing a passage for the exhaust

gases to flow freely thru the Venturi tube end of the valve cylinder into the exhaust manifold.

It will be noted that by reason of the passage 47 surrounding the movable sleeve valve, the effect of the explosion is distributed evenly around the entire valve, so that there is no tendency for the valve to stick during the ignition of the fuel. It will also be noted that at the moment of explosion, the selector 61 covers the ports 50, thus providing a double assurance against the passage of the flame back to the intake manifold. The exhausting burned gases are of course very hot and the heavy bushing 54 offers not only a mechanical protection and shield to the lighter parts which it covers, but also tends to dissipate the absorbed heat by reason of its thermal contact with parts over which cooling water flows. Since the bushing necessarily obstructs the passage, the interior orifice is given the Venturi shape to increase the velocity of the gases at this point. Although the drawings, particularly Figure 1, disclose the ports 50 and 58 as comprised of aligned slots separated by a narrow bridge, it is to be understood that the bridge portion is merely to strengthen the two parts which would otherwise be separated and that the sleeves are not thereby doubly ported. There is but a single port 48 at the top of the explosion chamber in each cylinder and the apertures in the sleeves are to be considered as single ports, since they are in effect that and the bridge separating the two portions of the port in each sleeve could be omitted if desired.

In order to protect the various working parts of the engine, it is preferable to enclose it and this is done by providing a housing 93 over the rocker arms and cam shaft and in which is left an opening adjacent the cam shaft normally closed by the door 94. A similar housing 96 encloses the float chamber, carburetor and distributor and an opening normally closed by the door 97 gives access to the protected parts.

I claim:

1. In an internal combustion engine, a main cylinder, a piston in said main cylinder, a valve cylinder opening at one end into the exhaust manifold and at the other end into the inlet manifold and having a port opening into the main cylinder, a ported sleeve slidably arranged to control the cylinder port, a selector disposed within the sleeve and movable from one side of the cylinder port to the other, and means acting in time with the piston for actuating said sleeve and selector.

2. In an internal combustion engine, a main cylinder, a piston in said main cylinder, a valve cylinder opening at one end into the exhaust manifold and at the other

- end into the inlet manifold and having a port opening into the main cylinder, a ported sleeve slidably arranged to control the cylinder port, said port opening in a passage 5 surrounding said sleeve, a selector disposed within the sleeve and movable from one side of the cylinder port to the other, and means acting in time with the piston for actuating said sleeve and selector.
- 10 3. In an internal combustion engine, a main cylinder, a piston in said main cylinder, a valve cylinder opening at one end into the exhaust manifold and at the other end into the inlet manifold and having a port opening into the main cylinder, a ported sleeve slidably disposed in the valve cylinder to control the cylinder port, a selector disposed within the sleeve and movable to connect the cylinder port with either 15 end of the valve cylinder, and means acting in time with the piston for actuating said sleeve and selector.
- 20 4. In an internal combustion engine, a main cylinder, a piston in said main cylinder, a valve cylinder opening at one end into the exhaust manifold and at the other end into the inlet manifold and having a port opening into the main cylinder, a ported sleeve slidably disposed in the valve cylinder to control the cylinder port, a fixed 25 sleeve extending into the slidable sleeve and having a port in register with the cylinder port, a selector slidably arranged in the fixed sleeve and movable from one side of the port therein to the other, and means acting in time with the piston for actuating the slidable sleeve and selector.
- 30 5. In an internal combustion engine, a main cylinder, a piston in said main cylinder, a valve cylinder opening at one end into the exhaust manifold and at the other end into the inlet manifold and having a port opening into the main cylinder, a ported sleeve slidably disposed in the valve cylinder to control the cylinder port, a selector disposed within the sleeve and movable to connect the cylinder port with either 35 end of the valve cylinder, rocker arms respectively connected at one end to each of said sleeve and selector and pivoted at the other end, a cam shaft driven meditately by the piston and cams on said shaft for imparting motion to said rocker arms.
- 40 6. In an internal combustion engine, a main cylinder, a piston in said main cylinder, a valve cylinder having a port opening into the main cylinder, a ported sleeve slidably disposed in the valve cylinder to control the cylinder port, a fixed sleeve 45 within the slidable sleeve and having a port in register with the cylinder port, a selector slidably arranged in the fixed sleeve and movable from one side of the port therein to the other, means acting in time 50 with the piston for actuating the slidable sleeve and the selector, a fuel passage connected into one end of the fixed sleeve, and an exhaust passage connected into the other end.
- 55 In testimony whereof, I have hereunto set my hand.
